UNITED STATES PATENT OFFICE.

ALBERT TURNER, OF SHREWSBURY, MASSACHUSETTS, ASSIGNOR, BY MESNE ASSIGNMENTS, TO CINCINNATI GRINDERS INCORPORATED, OF CINCINNATI, OHIO, A CORPORATION OF OHIO.

ROLL-GRINDING MACHINE.

Application filed March 12, 1925. Serial No. 15,053.

This invention has reference to improvements in grinding machinery and more particularly to precision grinding apparatus employed in the production of work of circular shape in cross section.

Such machinery in its broad aspect ordinarily comprises a bed, a work supporting table, and a grinding wheel, one of the two latter parts being laterally shiftable with respect to the other, to cause a relative traversing movement of the work and tool or grinding wheel when in operation.

The particular type of mechanism with which we are here concerned is that which is adapted for the production of either straight or plain cylindrical rolls, shafts, or the like, or for the production of work pieces which may be frusto-conical, or of cambered shape; that is to say, work pieces which are of circular shape in cross section, but have some form of straight or curved longitudinal taper.

Such work pieces in one adaptation are employed in metal rolling mills, where subject to very heavy terminal pressure, the purpose of the taper formation being that the roll, which might otherwise spring centrally and bear unevenly on the metal being rolled, on account of its swelled central formation, when sprung under pressure, will tend to change from a bowed contact surface to a straight lower line of contact. It will be understood that rolls of this character are formed from quite heavy stock, frequently 6" to 12" in diameter, and that the amount of tapering toward the ends is but slight, being measurable, for example, by thousandths of an inch, but nevertheless of prime importance in production of proper rolled stock.

It is therefore the purpose of the present invention to provide a simple rugged and readily adjustable mechanism, which may be employed for precision grinding of either straight cylinders or of tapering rolls, such as just mentioned, and which in either event will produce work accurate to within .001".

A further object of the present invention is the provision of a machine for the purpose mentioned, which will automatically produce and preserve on the periphery of the stone a complementary curve to that which is desired on the finished article.

An additional object of the invention is

the provision of an improved structure for the intended purpose, which may be readily applied to present commercial forms of grinding machines without material alteration in the existing parts thereof.

Other objects and advantages of the invention should be readily apparent by reference to the following specification taken in connection with the accompanying drawings illustrative of one embodiment thereof. It is to be understood that I may make any modifications in the specific details of construction or combination and arrangement of parts hereinafter disclosed within the scope of the appended claims without departing from or exceeding the generic principles of the invention.

Fig. 1 represents a perspective view of a grinding machine embodying my invention.

Fig. 2 represents a plan view thereof.

Fig. 3 represents an enlarged fragmentary plan view of a slightly modified construction.

Fig. 4 is a semi-diagrammatic plan view illustrating the adjustment of parts for the production of concaved work.

Fig. 5 is a similar view showing the parts laterally shifted for truing the active face of the grinding wheel.

Fig. 6 is a section on the line 6—6 of Fig. 2.

Figure 7 is a horizontal section through one of the guide members and associate parts, taken on line 7—7 of Figure 1, and

Figure 8 is a vertical section as on line 8—8 of Figure 2.

In the drawings, the reference character A designates the bed of a precision grinder having the ways B for the table C and having bearings D for the grinding wheel or tool member E—these parts being of usual and well-known construction and not requiring further detailed description. The bearings D are ordinarily mounted upon a transverse slide F, so that the wheel may be moved toward and from the work for proper feeding action.

In the present invention, there is mounted upon table C a second or supplemental swinging table member 10, which may be pivotally supported on table C by stud 11 for longitudinal movement with the table and transverse oscillation with respect thereto. This supplemental table is provided with the suitably driven headstock G and

tailstock H for supporting and rotating the work in opposition to the grinding wheel E.

Suitable feed mechanism (not illustrated) serves to automatically longitudinally shift table C on ways B. In addition, the same may be manually shifted, as by actuation of the control wheel I. In normal operation, that is to say in the production of ordinary cylindrical work, the tables 10 and C may

10 be rigidly connected in any suitable manner.

When it is desired to produce cambered or centrally swelled or concaved rolls or work pieces, it is desirable that the swivel table 10 be allowed to swing on table C and thus 15 generate the desired curve. This generating action will be most readily understood by reference to Figure 3.

It will be understood that the members 17 and 18 are supported on the bracket or frame 20 blocks 31 which are carried by the bed A of the machine through the medium of the pivots 32. These pivots hold the guides sufficiently spaced from the bed of the machine to permit of desired angular adjustment thereof as will be readily apparent by reference to Figures 7 and 8.

Since the adjustments in question are frequently of very minute amount, due to the slight camber to be produced on the roll 30 being ground, difficulty might be experienced in accurate adjustment with ordinary screw mechanisms. I have therefore found it most advantageous to employ the pair of set screws 33 and 34 near opposite ends of the 35 guide member and of length to project into suitable engagement with the bed A of the machine. By loosening one of these screws and tightening the other the proper angular adjustment of the guide may be effected to 40 within very fine limits.

To properly cooperate with these guides there are secured at the ends of the supplemental table 10 the pair of forwardly curved arcuate arms 13 and 14 having suitably 45 journaled therein the trunnions 19 and 20 respectively of the guide engaging shoes 15 and 16. It will thus be noted that with the machine properly assembled the shoes 15 and 16 will be in engagement with and 50 ride along the adjustable guides 17 and 18 and on account of their pivotal connection to the arms 13 and 14 will automatically adjust or accommodate themselves to the angles at which the guides may be set through 55 adjustment of screws 33 and 34.

In the operation of the machine constructed in accordance with this invention the main table is given a longitudinal feeding movement across the face of the grinding wheel. This correspondingly laterally shifts the supplemental or swinging table 10 on account of the pivotal connection at 11 holding the parts against relative longitudinal movement. If the guide members 17 and 18 are set in a position parallel with the ways B

on table C, the supplemental table 10 will have no swinging movement but merely a traversing movement so that straight cylindrical work will be produced by the grinding action. However, if the members 70 17 and 18 are set at a slightly convergent angle as indicated in Figures 2 and 3 for example, the guide at the side toward which the table is moving will exert a pulling action camming its contact shoe outwardly 75 and thus swinging that end of the table outwardly so that the wheel will bite in more deeply at the opposite end of the work piece. The engagement of the contact shoe and guide at the opposite end of the table limit 80 this inward swinging as long as the table continues in the one direction and serves to reversely swing the table as it moves in the opposite direction. It will thus be seen that with the slight angular adjustment of the 85 guides shown in Fig. 2 there will be generated a slight arc longitudinally of the work piece and the amount of this arc will vary with the angle imparted to the guides. Similarly, if the guides be set in divergent 90 relation as indicated in Fig. 4 the swinging will be in the opposite direction.

Since the shoe 16 will exert the tractile effort as the table 10 is moved to the left, moving that end of the table outwardly so 95 that the diameter of the roll gradually increases from center to end while the shoe 15 limits the inward swinging movement. As the generated path is of circular form the grinding wheel will be symmetrically 100 worn away so that not only is the proper curve generated on the work piece but the generative movement thereof serves to preserve the contour of the grinding wheel for proper surface grinding rather than line 105 grinding.

To supplement this action a truing device such as K may be mounted in the tailstock so that on continued traversing movement of tables bringing the tailstock 110 even with the wheel the truing device may operate upon the wheel surface to restore it to proper cutting condition and at the same time true it to the desired generative curve.

In the form shown the table and arms are 115 illustrated as of considerable length while as the angle of the guides may be adjusted to very fine limits by the screw mechanism employed it is possible to produce on the work a barrel like or tapered cylindrical effect 120 varying as little as a few thousandths of an inch from center to end, or in other words, to adjust the amount of normal center swell of a heavy roll so that when in use working pressure applied to the ends of the roll will 125 simply flatten the contacting surface thereof to a straight line in place of allowing it to spring in the middle and produce unequal transverse pressure as would otherwise be the case.

It will thus be seen that the amount of swinging movement of the table may be varied within exceeding fine limits by a mere changing of the angle of the guides and the 5 precise curve desired generated without the use of templates or other mechanism.

In those instances where there is to be but a very slight cambering of the work piece, the pivot stud 11 may simply be journaled in table 10, which has sufficient spring 10 to allow for the necessary forward movement of the head or tailstock as the parts are reciprocated on the bed. When greater amount of cambering or tapering is desired, 15 however, or, in any event, if preferred, the stud 11 may be rigidly secured to one table and have transverse sliding movement in the other; that is to say, it may, for example, be journaled in table 10, and have on its 20 lower end a block 26 sliding in slot 27 in table D, preferably being urged in the direction of the stone as by interposed spring 28.

In addition, to aid in controlling the 25 position of the swivel table 10 on the sliding table C, table C is provided with a plurality of brackets 29, while interposed between said brackets and table 10 are the heavy coil springs 30, exercising a pressure forcing the 30 table inward toward the stone. This movement is of course limited by the interengagement of the shoes 15 and 16 with the guides 17 and 18 and varies with the arcuate adjustment of the swivel table. Suitable 35 adjusting devices 31 may be provided for varying the tension or pressure of the several springs. This is desirable, since the springs perform a double function. Primarily they urge the table and work toward 40 the grinding wheel. In addition, they are necessary to overcome the inertia of the table toward swinging movement, due to the weight of the part 10, the work-supporting and driving members mounted thereon, and 45 the friction between member 10 and table C. If these springs were not present to overcome this inertia the outwardly riding arm 13 would spring or bow the table and thus the work before the opposite end of the 50 table would begin its swinging movement. While the effect here would be relatively slight, it might produce an error of several thousandths in the diameter of the work at the particular point affected—a serious 55 matter in a machine designed for accuracy within the limits of less than .001".

The tension of the springs is so adjusted as to overcome this friction inertia and tend at all times to force the table in and hold 60 the adjacent contact shoe in tight engagement with its guide.

Briefly stated, in use the work is mounted on swivel table 10 between the head and tailstock members and the guides 17 and 18 65 are set at equal angles to the table being in

convergent relation for convex work and divergent relation for concave work, as will be understood by comparison of Figures 2 and 4. A longitudinal movement is then given the slide table C on its ways and the work is shifted back and forth across the grinding wheel, the table 10 being longitudinally moved therewith on account of the interengagement of the pivot stud 11 with the two tables. As the tables are moved 75 back and forth shoes 15 and 16 riding on guides 17 and 18 will cause the swinging movement previously described to be imparted to table 10 and thus to the work piece, generating a proper curve on the work 80 piece. At the same time, on account of this generation of the curve by the swinging, a similar contrageneric curve will be produced on the periphery of the stone, so that the entire transverse operative surface of 85 the stone will continuously be in contact with the work, obtaining maximum grinding efficiency, also a transverse continuous contact engagement of the work wheel, tending to keep the stone true.

I claim—

1. A machine of the character described including a tool, a support adjacent the tool, a table movable over the support, means for longitudinally shifting said table, and means for oscillating the table as it is reciprocated, said latter means including a longitudinally shiftable positioning pivot for the table, spaced arms projecting from the table and angularly related guides on the support engaging said arms.

2. A grinding machine including a bed, a grinding wheel supported thereby, ways on the bed extending transversely of the operative face of the grinding wheel, a table movable along said ways, a supplemental work supporting table mounted thereon, a pivot connecting the main and supplemental tables for joint linear and relative oscillatory movements, arms on the supplemental table extending forwardly therefrom, contact shoes pivotally secured to the arms, guide members on the bed in position for engagement by the shoes, and means for independently angularly adjusting the position of the guide members with respect to the bed.

3. A grinding machine including a bed, a grinding wheel supported thereby, ways on the bed extending transversely of the operative face of the grinding wheel, a table movable along said ways, a supplemental work supporting table mounted thereon, a pivot connecting the main and supplemental tables for joint linear and relative oscillatory movements, arms on the supplemental table extending forwardly therefrom, contact shoes pivotally secured to the arms, guide members on the bed in position for engagement by the shoes, means for independently

angularly adjusting the position of the guide members with respect to the bed, and individual pressure devices adjacent the arms for individually urging the shoes of the arms into engagement with the adjacent guides.

5. A grinding machine including a bed, a grinding wheel carried thereby, ways on the bed extending transversely of the operative face of the grinding wheel, a main table 10 movable along said ways, a supplemental table carried by the main table, a pivot non-translatably mounted in one of said tables and supported for limited sliding movement with respect to the other of said tables, an- 15 gular guides carried by the bed, arms on the supplemental table having portions for engagement with the guides, and resilient means for centrally and terminally urging the supplemental table in the direction of the 20 grinding wheel.

6. A grinding machine including a bed, a grinding wheel carried thereby, ways on the bed extending transversely of the operative face of the grinding wheel, a main table movable along said ways, a supplemental table pivoted to the main table and having terminal arms curving forwardly therefrom, said arms terminating in depending contact shoes, guides on the bed 45 in position to engage the shoes, and means for individually angularly adjusting the guides to vary the effective engagement thereof with the shoes on the arms.

7. A grinding machine of the character described, including a bed, a grinding wheel supported by the bed, ways on the bed extending transversely of the operative face of the grinding 40 wheel, a main table movable along said ways, a supplemental table pivoted to the main table and having terminal arms curving forwardly therefrom, said arms terminating in depending contact shoes, guides on the bed 45 in position to engage the shoes, and means for centrally and terminally urging the supplemental table in the direction of the grinding wheel, and means for adjusting the effective pressure of the resilient means.

8. A machine of the character described, including a bed, a grinding wheel supported by the bed, ways on the bed extending transversely of the operative face of the grinding wheel, a main table movable along said ways, a supplemental table pivoted to the main table and having terminal arms curving forwardly therefrom, said arms terminating in depending contact shoes, guides on the bed 45 in position to engage the shoes, and means for individually angularly adjusting the guides to vary the effective engagement thereof with the shoes on the arms.

In testimony whereof I hereunto set my hand this 5th day of March, 1925, at Cincinnati, Ohio.

ALBERT TURNER.
